(57) **CLAIM**

The ornamental design for a registration pocket, as shown and described.

DESCRIPTION

FIG. 1 is a front elevational view of the registration pocket of the present invention;

FIG. 2 is a back elevational view of the registration pocket of FIG. 1;

FIG. 3 is a left side elevational view of the registration pocket of FIG. 1;

FIG. 4 is a right side elevational view of the registration pocket of FIG. 1;

FIG. 5 is a top plan view of the registration pocket of FIG. 1;

FIG. 6 is a bottom plan view of the registration pocket of FIG. 1; and,

FIG. 7 is a front, top, right side perspective in use view of the registration pocket of FIG. 1.

The broken lines showing the interior of a vehicle in FIG. 7 are for illustrative purposes only and form no part of the claimed design.
